US0D1043638S

(12) **United States Design Patent** (10) Patent No.: **US D1,043,638 S**
(45) Date of Patent: ** Sep. 24, 2024

(54) **ROUTER**

(71) Applicant: **Charter Communications Operating, LLC**, St. Louis, MO (US)

(72) Inventors: **Ethan Miller**, Parker, CO (US); **Chelsea Young**, Englewood, CO (US); **Ian Ruppert**, Denver, CO (US); **Srinivasa Ramani**, Aurora, CO (US)

(73) Assignee: **Charter Communications Operating, LLC**, St. Louis, MO (US)

(**) Term: **15 Years**

(21) Appl. No.: **29/882,237**

(22) Filed: **Jan. 12, 2023**

(51) LOC (14) Cl. **14-03**

(52) U.S. Cl.

USPC **D14/242**

(58) **Field of Classification Search**

(57) **CLAIM**

The ornamental design for a router, as shown and described.

DESCRIPTION

FIG. 1 is a front right perspective view of the router.

FIG. 2 is a back left perspective view of the router.

FIG. 3 is a front side view of the router.

FIG. 4 is a back side view of the router.

FIG. 5 is a right side view of the router.

FIG. 6 is a left side view of the router.

FIG. 7 is a top view of the router; and,

FIG. 8 is a bottom view of the router.

The broken lines shown in FIGS. 1-8 represent portions of the router that form no part of the claim.

The logo trademark forming part of the disclosure is a registered trademark of Charter Communications Holding Company, LLC.

1 Claim, 7 Drawing Sheets
